(57) **CLAIM**

The ornamental design for a plant pot, as shown and described.

DESCRIPTION

FIG. 1 is a perspective view of the plant pot showing my new design;

FIG. 2 is a perspective view thereof from another angle;

FIG. 3 is a front/rear/right/left elevational view thereof;

FIG. 4 is a top plan view thereof; and,

FIG. 5 is a bottom plan view thereof.

The broken lines in the figures illustrate portions that form no part of the claimed design.
